PROCESS OF THE MANUFACTURE OF CARBURETED WATER GAS WITH HEAVY OIL

Joseph A. Perry, Swarthmore, Pa., assignor to
The United Gas Improvement Company, Philadelphia, Pa., a corporation of Pennsylvania

Application February 7, 1931, Serial No. 514,106

4 Claims. (Cl. 48—205)

The present invention relates to the manufacture of carbureted water gas.

It is particularly adapted to the manufacture of carbureted water gas when employing heavy oils and residuums as the carbureting material.

By heavy oils I mean to include those oils which when vaporized in the ordinary checker filled carburetor produce excessive deposition of carbon on the checkerbrick and due to the deposited pitch cause excessive deposition and retention in the checkerbrick, of fuel and ash from the generator with consequent stoppage of the gas passages of the carburetor. These heavy oils vary greatly in composition. As an example may be mentioned the so-called "bunker oils". These may consist of topped crude oils and may or may not contain varying quantities of tar. These heavy oils and residuums on vaporization yield more coke than ordinary gas oils.

Because of the above it is not good practice to vaporize these oils in the ordinary checker filled carburetor. There are better methods, as for instance, vaporizing the oil on the top of the generator fuel bed during the run after the top of the fuel bed has been specially heated during the blow by the combustion, with secondary air, of the producer gas generated by the primary air blast, or vaporizing them by spraying them by means of a nebulizing spray into a heated carburetor devoid of checkerbrick, or a combination of these methods.

Whichever method is employed it is a characteristic of these oils and residuums, that although for rapid vaporization they require more heat than ordinary gas oil, the resultant vapors require less heat for fixing to oil gas.

In ordinary operation with gas oil, the fuel bed is blasted and the resultant producer gas burned and its heat stored in the carburetor and superheater. The oil is vaporized during the run (sometimes only during the uprun) in the carburetor and the resultant oil vapors with the water gas traverse the carburetor and superheater where the oil vapors are fixed to oil gas without overcracking.

In operation with heavy oil, however, the exposure of the oil vapors to the quantity of heat so stored and the temperature conditions so established, leads to overcracking.

This overcracking is particularly undesirable where a tar is desired which can be used for the manufacture of road compounds. It is now common practice to use water gas tar in the manufacture of such compounds, as a thinner for coal gas tar. The tar produced from heavy oil under

the above described conditions of overcracking is likely to be heavier than coal gas tar and useless as a thinner. Its value as a fuel is only a fraction of its value as a road compound material.

It is the principal object of the present invention to provide a method of and apparatus for the manufacture of carbureted water gas employing heavy oil which is free from the above disadvantages of overcracking. According to the present invention the proper heat storage conditions are set up for the vaporizing of the heavy oil and fixing the resultant vapors, while the heat of the blast gases is efficiently recovered.

Generally stated the invention includes air blasting an ignited fuel bed to store heat therein, burning the resultant producer gas with secondary air in the oil vaporizing portion of the heat storage and storing a portion of its heat therein, dividing the resultant blast gas and passing one part through the oil vapor fixing portion of the heat storage and thence through the waste heat boiler to raise steam, and by-passing the other part around the oil fixing portion of the heat storage and thence through the waste heat boiler. Prior to passage of the gases through the waste heat boiler tertiary air is added to substantially complete combustion before reaching the boiler tubes.

I prefer to admit the tertiary air to the by-passed portion of the gas in the by-pass pipe carrying the gas to the waste heat boiler, completing combustion substantially in the pipe.

The invention will be further described in connection with the following figures, which form a part of this specification and which show forms of the apparatus of the invention chosen for illustration, and in which,

Figure 1 shows a partial elevation and partial vertical cross section of a carbureted water gas set with provisions for vaporizing oil on the top of the fuel bed.

Figure 2 shows a partial elevation and partial vertical cross section of a carbureted water gas set with provisions for vaporizing oil in an empty carburetor.

Referring to Figure 1,

1 is the generator. 2 an ignited fuel bed therein. 3 is an air supply means for up air blasting. 4 is a steam supply means for up steaming. 5 is an air supply means for admitting secondary air peripherally adjacent the top of the fuel bed, and includes the bustle pipe 6 and connections 7. 8 is an oil supply means arranged to spray oil onto the marginal ring heated by secondary combustion. The generator is further provided with the

connection 9 provided with valve 10 leading to the carbureter 11. There is thus provided a gas conduit connecting generator 1 and the oil vaporization apparatus, which is located above the generator. The carbureter is provided with checkerbrick and in communication by connection 13 with the superheater 14. 15 indicates the superheater checkerbrick.

The superheater is provided with stack valve 16 and with the gas offtake 17 leading to waste heat boiler 18.

The waste heat boiler is connected also to the stack 19, provided with stack valve 20.

The superheater is further provided with the steam supply means 21 for down running, with the tertiary air supply means 22, and with the gas offtake 23 leading through the reversing valve 24 to the washbox 25. 27, provided with valve 26, is the offtake from the washbox to storage or other disposal. The generator is provided with the gas offtake 28 leading from below the fuel bed to the washbox by way of valve 24.

There is further provision of the by-pass connection 29 provided with valve 30, leading from the generator to the waste heat boiler. 31 is an air supply means for admitting tertiary air to connection 29.

In operation the fuel bed is blasted with air supplied through 3 and the resultant producer gas burned in whole or in part by secondary air supplied through 5, 6 and 7, producing besides the usual hot water gas reaction zone, a marginal hot zone at the top of the fuel bed.

The resultant gases leave the top of the generator and are divided, one portion passing through connection 9 and valve 10 to the carbureter 11, and thence through the carbureter and superheater in series and through the waste heat boiler to the stack 20, storing heat on the carbureter and superheater and raising steam in the boiler. Air for tertiary combustion is admitted at 22, if necessary.

The other portion is by-passed around the carbureter and superheated to the waste heat boiler by way of connection 29 and valve 30. Air for tertiary combustion is admitted to the connection 29 at 31, if required to ensure substantially complete combustion before reaching the waste heat boiler. The burned gases pass through the boiler raising steam and exit from the stack valve 20.

During this operation, according to a cycle chosen for illustration, valves 10, 30 and 20 are open, valve 16 is closed, and reversing valve 24 is set to close line 28. The relative proportion of gas passed through the carbureter and superheater and by-passed to the boiler will depend on the relative opening of the valves 10 and 30. Preferably the valves would be opened wide and the quantity of gas passed through connections 9 and 29 controlled by brick dampers on these connections.

As an alternative to the simultaneous passage of gas through connections 9 and 29, all of the gas may be alternately passed through 9 and 29 by appropriately controlling valves 10 and 30. This alternation may take place within a single cycle or not.

After the air blow step, an uprun is made with steam supplied at 4, the resultant water gas is carbureted with oil supplied through 8 and sprayed onto the marginal hot zone at the top of the fuel bed. The resultant oil vapors together with the water gas pass through connection 9 and through the carbureter and superheater

where the vapors are fixed to oil gas. The resultant carbureted water gas passes through connection 23 to the washbox and thence through connection 26 to storage. During this step valves 16, 20 and 30 are closed. Valves 10 and 26 are open, and the reversing valve 24 is set to open line 23 and close line 28.

After the uprun, a down run may be made by steam admitted at 21, passed through the superheater and carbureter in series, and superheated 10 therein, and thence through the generator fuel bed, the resultant water gas passing through line 28 to the washbox and thence to storage.

During this step valves 16, 20 and 30 are closed; valves 10 and 26 are open and the reversing valve 15 is set to close line 23 and open line 28.

After a short uprun, uncarbureted, as a purge, the cycle may be repeated.

In the above operation, the flow of the heating gases during the blow is controlled so that the 20 desired quantity of heat is stored in the carbureter and superheater for the proper fixing during the carbureting operation, thereby obviating the undesirable overcracking.

Referring to Figure 2,

32 is the generator, provided with the ignited fuel bed 33, and with the air supply means 34 and steam supply means 35 for up air blasting and steaming respectively. Gas offtake 36 leads from above the fuel bed to the carbureter 37 which is devoid of checkerbrick and is provided with the nebulizing oil spray 38.

The carbureter is provided with connection 39 provided with valve 40 and leading to the superheater 41. The superheater is provided with 35 checkerbrick indicated at 42.

43 is a stack valve and 44 a blast gas offtake leading to the waste heat boiler 45. 46 is the boiler stack provided with stack valve 47. The superheater is also provided with the gas offtake 40 48 leading through the reversing valve 49 to the washbox 50. 51 is the gas offtake from the washbox to storage or other disposal and is provided with valve 52.

The superheater, as illustrated, is also provided with the steam supply means 53 for down running and the tertiary air-supply means 54.

The generator is provided with the gas offtake 55 leading through the reversing valve 49 to the washbox.

According to this modification of the invention a by-pass connection 56 is provided leading from the carbureter to the waste heat boiler and provided with valve 57. Connection 56 is further provided with the tertiary air supply means 58. Secondary air is supplied to the carbureter through air supply means 59.

In operation of the apparatus of Figure 2, the generator fire is blasted with air supplied through 34, and the resultant blast products burned with 60 secondary air supplied through 59.

The blast gases pass through the carbureter 37, storing heat in the lining and are then divided, a portion passing through connection 39, valve 40, superheater 41, connection 44 and the waste heat boiler to the stack, the other portion passing through connection 56 and valve 57 to the waste heat boiler and thence to the stack, by-passing the superheater. Air is admitted to the connection 56 through air supply means 58, to complete the combustion of the blast products in connection 56, before reaching the waste heat boiler, to prevent burning of the tubes.

Air may be admitted through 54 to complete 75

the combustion of the portion of the blast gas traversing the superheater.

The portion of the blast gas traversing the superheater stores heat therein for fixing.

5 During this operation valve 43 is closed, valve 47 is open, and the reversing valve is set to close offtake 55. Valves 40 and 57 are controlled so as to divide the blast gases between the path through the superheater and the path through 10 the by-pass connection 56, providing the desired heat storage conditions in the superheater. The heat of the by-passed portion is recovered in the waste heat boiler, as is also the heat of the blast gases traversing the superheater.

15 Instead of securing the desired heat storage conditions by simultaneously traversing the superheater with one portion of the blast gases and by-passing it with another portion, valves 40 and 20 41 may be alternately opened and closed, passing all the blast gases through the superheater during one period, and all through the by-pass connection during another. This alternation may be within the cycle, or in succeeding cycles.

25 After the blast, an uprun may be made. During this step valves 43, 47 and 57 are closed, valves 40 and 52 are open and the reversing valve is set to close offtake 55 and open offtake 48. Steam is admitted to the fuel bed through 35. The resultant water gas passes through the carbureter 30 and superheater, where it is carbured with oil sprayed into the carbureter through oil supply 38, the resultant vapors being fixed to oil gas in traversing the superheater. The resultant carbured water gas passes through offtake 48, reversing valve 49, the washbox 50 and offtake 51 to storage.

35 After the uprun a down run may be made with steam supplied through 53. The valve 49 is reversed, closing offtake 48 and opening offtake 55. The other valves remain set as in the uprun.

40 The steam passes through the superheater and carbureter, being superheated therein and thence to the generator where it passes down through the fuel bed. The resultant water gas passes 45 through offtake 55, valve 49, washbox 50 and connection 51, to storage.

45 After the uprun a short uncarbured uprun may be made and the cycle repeated.

50 The above operation is given as an illustration and I do not wish to be limited to the precise steps and order of steps above described.

55 I do not intend to be limited in the practice of my invention save as the scope of the prior art and of the attached claims may require.

I claim:

1. Process of manufacturing carbured water gas in a device including a generator containing an ignited fuel bed, a hydrocarbon vaporization apparatus, and a heat exchange apparatus, which process includes the following steps: one step being, air blasting the fuel bed to incandescence, passing all the blast gases through the vaporization apparatus, burning the blast gases in the vaporization apparatus, dividing the flow of blast gases as it issues from said vaporization apparatus, conducting one portion through the heat ex-

change apparatus storing heat therein to the amount desired, by-passing all of said heat exchange apparatus with the remaining portion of the blast gases to prevent overheating the heat exchange apparatus, and recovering outside of 5 said heat exchange apparatus the heat of the blast gases not stored in the heat exchange apparatus; and another step being, introducing steam to the fuel bed, generating blue water gas thereby, carbureting the blue water gas, and 10 utilizing in the gas-making process the heat stored in said heat exchange apparatus.

2. Process of manufacturing carbured water gas, which process comprises the following steps: one step being, air blasting an incandescent bed 15 of solid fuel, burning the resulting blast gases with secondary air in a vaporization zone thereby storing heat in said vaporization zone, dividing said blast gases passing from said vaporization zone into two streams, storing at least a portion 20 of the remaining heat of one of said streams in a fixing zone by leading said stream through said fixing zone, and by-passing the other stream with respect to and out of contact with all of said fixing zone; and another step being, passing 25 steam through said fuel bed thereby generating blue water gas, simultaneously introducing heavy oil to said vaporizing zone and vaporizing said heavy oil in said zone, and passing said blue 30 water gas and the oil gas and oil vapors resulting from the vaporization of said heavy oil through said fixing zone thereby carbureting said blue water gas.

3. A step in an intermittent process of manufacturing carbured water gas, which step includes air blasting an incandescent fuel bed, burning the resulting blast gases with secondary air introduced adjacent the upper edge of the fuel bed, dividing the blast gases from the fuel bed into two streams, storing at one place at least a portion of the heat of the blast gases in one stream, for use in the gas making process by leading said stream through said place, by-passing the blast gases constituting the other stream around all of said place at which said heat is stored to prevent over-heating said place, and utilizing heat stored at said place in the gas-making process.

4. In a process of manufacturing carbured water gas, the following steps: one step being, air blasting an ignited bed of solid fuel, burning the resulting blast gases with secondary air in a combustion space and storing heat therein, and then storing a selectively controlled portion of the remaining heat of said blast gases in a fixing zone by by-passing a portion of said blast gases around all of said fixing zone; and another step being, steam blasting said fuel bed thereby generating blue water gas, introducing heavy oil directly into the combustion space and carbureting said blue water gas with the vapor resulting from the vaporization of said heavy oil, and fixing said heavy oil vapors in said water gas by means of the heat stored in said fixing zone.

JOSEPH A. PERRY.
